UNITED STATES PATENT OFFICE

2,500,226

PUMP ASSEMBLY

Harold E. Adams, Norwalk, Conn.

Application September 19, 1945, Serial No. 617,360

14 Claims. (Cl. 103—5)

1
 The present invention relates to a pumping unit and is an improvement on the general type of pumping unit shown, described and broadly claimed in my copending application Serial No. 658,471, filed March 30, 1946. One object of the present invention is the provision of such a unit combining the characteristics of a self-priming centrifugal pump with a positive type rotary pump to give high capacity, vapor-free delivery of liquid fuel at low pressure and also to give low and intermediate capacity delivery of liquid fuel at high pressure when required. Such a pumping unit is particularly useful in connection with aircraft engines requiring high performance and employing atomizing fuel nozzles for either reciprocating type engines or for revolving gas turbine driven engines and/or jet propulsion. It may, however, be used on other applications requiring similar performance and this invention is not intended to be restricted to this particular field.

A typical application of the pumping unit of the present invention is that of the newly developed art of jet propulsion. Gas turbines employed in this type of propulsion require fuel to be delivered to the atomizing burner nozzles at relatively high pressure such as 300 to 1000 p. s. i. For this purpose, high pressure fuel pumps are normally employed, these pumps being of the gear or piston type or of multi-stage centrifugal type, as exemplified in my Patent No. 2,438,104.

Incorporated with the main fuel pump is a system of by-pass or throttle control which automatically varies the amount of fuel required by the engine to maintain its desired speed over varying altitudes. It is a characteristic of this type of propulsion that the fuel requirements decrease with the altitude and unless the fuel is automatically reduced in proportion to the altitude, there is danger of the engine burning up from over-speeding and over-heating. The main engine fuel pump and its control therefore perform a vital function in the successful operation of the airplane and any failure in either the fuel pump or its control would result in possible loss of the airplane.

These jet propelled units are also equipped to burn almost any type of fuel including highly volatile, high octane gasoline fuels principally used on reciprocating type engines. The use of such highly volatile fuel subjects the fuel system to additional difficulty because of the non-lubricating qualities of the gasoline, which tends to wear out the fuel pump, and also because of the vaporization in the fuel suction lines to these

5 pumps, which causes vapor lock and pump failure.

The use of a fuel booster pump placed in the fuel tank and operating to pressurize the line from the fuel tank to the main engine fuel pump is generally practiced and such pumps as covered in my Patent No. 2,461,865 have been quite successfully used. These centrifugal type fuel booster pumps are only capable of low pressure delivery, which is sufficient to overcome the possible vapor lock formation in the fuel lines. It is highly desirable that such pumps be capable of delivering fuel under high pressure conditions upon emergency, as for example, in case of failure of either the main engine fuel pump or its control.

In accordance with my invention, I include new and improved means for handling the large capacity requirement at low pressure for the purpose of pressurizing the main fuel lines to prevent 10 vapor lock, and also include pumping means which automatically or manually come into action when the requirement arises for starting or for emergency duty at high pressure.

In this structure I use for the high pressure 15 service a vane type rotary pump which heretofore has only been suitable for application on relatively low pressure service such as 35 to 65 p. s. i. I make it possible for these pumps to deliver fuel against pressures up to 350 p. s. i. and higher. The vane pump also serves as additional scavenging means to aid in priming the 20 centrifugal pump.

Various other features and advantages of the 25 invention will be apparent from the following 30 particular description and from an inspection of the accompanying drawings, in which:

Fig. 1 is a side view of an embodiment of this 35 invention in connection with a mounting on the bottom wall of a fuel tank;

Fig. 2 is the bottom plan view of the pump;

Fig. 3 is a cross-sectional view taken along line 40 3—3 of Fig. 2;

Fig. 4 is a cross-sectional view taken along the 45 lines 4—4 of Fig. 2 with the conduits shown in Fig. 5 superimposed diagrammatically; and

Fig. 5 is a diagrammatic sectional view of the 50 pump unit of the present invention, said sectional view being distorted from the actual relationship of the parts indicated in Figs. 1 to 4 in order to show more clearly the relationship between the passages and the different pump units.

Referring to the drawings, there is shown a 55 fuel tank 10 having a wall 11 such as a bottom wall with an opening 12 through which the pump unit of the present invention passes. This pump

unit comprises a body 13 having a flange 14 by which said unit is sealably bolted or otherwise fastened by a leak-proof connection to the bottom tank wall 11, so that the tank opening 12 is sealed. The pump unit is shown including three sections 13, 15 and 16 bolted or otherwise fastened together, and surmounted by an electric motor 17 adapted to drive a centrifugal booster pump 18, a liquid ring type pump 19 for removing the vapor from the fuel in said booster, and a rotary vane type fuel pump 20. For driving these different pumps from the motor 17, the motor shaft 21 is connected to the centrifugal impeller pump shaft 22 by a flexible coupling 23, and a pinion 24 on said impeller pump shaft meshes with a gear 25 on the shaft 26 of the fuel pump 20.

The entire pump unit is of such a height as to be completely submerged in the fuel which is to be pumped from the fuel tank 10. The fuel inlet to the centrifugal booster pump 18 is through a strainer 30. From this strainer inlet 30, the fuel is divided between an upper inlet chamber 31 and a lower inlet chamber 32. The booster pump 18 has a double suction centrifugal impeller 33 with an upper eye 34 and a lower eye 35, the fuel flowing into these eyes from the inlet chambers 31 and 32 respectively.

In Fig. 5, the pump unit of Figs. 1-4 is shown diagrammatically, but is shown mounted on the side wall of the fuel tank, instead of on the bottom wall of said tank. However this showing in connection with a side wall mounting is made to indicate that the pump unit of Figs. 1-4 can be so mounted. In all other respects, the pump unit is similar to that of Figs. 1-4.

As shown diagrammatically in Fig. 5, the booster pump impeller 33 discharges into a volute 37, which in turn discharges into two branch passages 38 and 39. Under normal operating conditions, the main flow of the centrifugal pump is through the connection 38 through a discharge connection 41, and into a T-fitting 42 to a main high pressure fuel pump 43 on the outside of the fuel tank 10. From this main fuel pump 43, the fuel passes under high pressure through a check valve 44, and through a main fuel line 45 to the burner nozzles (not shown).

During the normal operation of the plane and the pump, there is an auxiliary amount of fuel discharged through the passage 39 into the inlet 47 of the vane fuel pump 20. This fuel is discharged from the vane pump 20 through an outlet 50 into a conduit 51, and from there through a discharge connection 52 to a T-fitting 53. The two fittings 42 and 53 are interconnected by a by-pass line 54 having a valve 55 which is normally opened. The high pressure fuel delivered by the main fuel pump 43 to the line 45 is prevented from flowing back through the T-fitting 53 by a check valve 56.

The motor 17 is completely enclosed by a pressure-tight housing formed by an upper bell casting 57, an intermediate cylindrical casting 58 and the lower bell casting 16. Liquid-tight gasket joints are formed between these three castings in any well-known manner. The bell casting 16 includes a rotating sealing member 59, which is in sealing engagement with a stationary bearing 70. The motor is thus protected from the ingress of liquid fuel from the tank. It is provided with a breather connection, which is not shown, and with a seal drain connection 71 to drain off any incipient leakage from the sealing member 59. There are also provided separate conduits (not shown) extending from

the inside of the motor 17 to the lower end of the pump casing, which contain the motor electric leads.

The pump 19 serves to remove vapors from the fuel in the pump 18 when handling volatile fuels, such as aviation gasoline. For that purpose, the casing of the pump 18 is provided near the two inlets 34 and 35 thereof with annular gas collecting grooves 60 and 61. The vapors collect in these annular grooves 60 and 61 by centripetal action, and are conducted into the inlet ports 62 and 63 of the liquid ring vapor removal pump 19 by means of the conduits 64, 65, 66 and 67. The general arrangement of the fuel booster pump 18 with the liquid ring vapor removal pump is shown in my Patent No. 2,461,865. The pump 19 discharges these vapors after compression through discharge ports 68 and 69 directly below the pinion 24 mounted on the pump shaft 22.

The liquid ring pump 19 discharges air, vapor and liquid upwardly along the pinion 24, and into a discharge chamber 73. The flowing of the fuel past the gears 24 and 25 effectively lubricates these gears. Ordinarily, gasoline would be ineffective for that purpose, because of its low lubricating properties. However, these gears 24 and 25 operate right in the gasoline and are lubricated effectively thereby, because of the high speed at which they operate, and because of the effect of the admixture of air and vapor which is discharged thereagainst by the pump 19 as described. Also, the agitation resulting from the gears 24 and 25 results in their running practically in a pocket of vapor and air bubbles. The breaking up of the fluid around the gears in this manner reduces the friction normally experienced when operating gears in a flooded condition.

The vapor and liquid are then discharged from the chamber 73 upwardly through ports 74 into an annular chamber 75 surrounding the stator windings of the motor 17. From here the liquid passes through additional ports 76 into another chamber 77 surrounding the airtight casing 57 housing the commutator and brush rigging 80 of the motor 17. The air and vapor are discharged upwardly through the top opening 81 of an outer motor casing 82 where they rise to the surface of the fuel in the tank, and the liquid overflows through the top of the chamber 77 over the upper annular edge 83 of the outer motor casing 82.

By means of the construction described, advantage is taken of the liquid discharged from the liquid ring vapor removal pump 19 as a means for effectively cooling the motor 17. This liquid is forced around the heated portions of the motor 17, so that by conduction, it removes the heat from said motor, thus enabling the motor to operate at high efficiency and with minimum dimensions. Since the motor 17 is liquid-cooled by the expedients described, this cooling is more effective than air cooling. It should be noted that the liquid cooling applied to the motor 17 exists at all times as long as there is any liquid in the tank 10, even though the liquid level in said tank may be below the level of the motor. In the case of the usual submerged fuel booster pump construction, the motor is not cooled by the liquid in the tank, if the level of the liquid in the tank drops below the level of the motor. Such an arrangement is generally satisfactory for small-powered motors, but where high input is required under emergency conditions, it is highly

advantageous to provide for a liquid cooling arrangement of the motor such as that of the present invention. This liquid cooling is obtained at no additional cost and power, since the discharge of liquid from the liquid ring vapor removal pump 19 is utilized for this purpose.

The motor 17 is equipped with internal stationary and rotating vanes (not shown) for the internal circulation of air through the field coils and armature to transmit further the heat from these parts to the side walls of the liquid-tight enclosure, which in turn transmits this heat to the circulated liquid by which the heat is carried away.

It should be noted that as a feature of the present invention, protection against vapor binding of the centrifugal pump 18 is additionally afforded by the arrangement of the vane type rotary pump 20. As already indicated, the liquid ring vapor removal pump 19 operates to clear of gas and vapor the suction side of the centrifugal volute in the pump 18. This arrangement is effective in maintaining vapor in bubble-free discharge from the centrifugal pump 18 when handling effervescent liquids, such as volatile aviation gasoline. Under extreme conditions, such as momentary uncovering of the suction, slipping, etc., the centrifugal pump 18 is liable to lose its prime. The liquid ring pump 19 will prime the centrifugal pump upon return of liquid to the centrifugal pump suction. However, in accordance with the present invention, the repriming is speeded up and aided by the action of the positive displacement rotary vane pump 20, because it exerts a continuous suction on the top of the volute 37 or centrifugal pump discharge 39, and therefore serves to constantly withdraw any gases or vapors collecting at this point. Thus, with the arrangement of the present invention, the centrifugal pump 18 is primed both from its suction side and its discharge side.

The vane pump 20 is in staged relationship with the centrifugal pump 18 for primary use as an emergency high pressure fuel pump. This vane pump 20 comprises a casing 90 having a cylindrical bore 91 in concentric relationship with respect to the pump shaft 26, and a rotor 92 affixed to said shaft. The vane pump 20 is of the sliding vane type having four vanes 93 arranged in quadrant relationship, with each set of two diametrically opposed vanes sliding in slots 94 in the rotor 92. In the central portion of the rotor 92 is located a pin 95, which maintains each opposite pair of blades in close proximity to the wall of the cylindrical bore 91 in the casing 90. This is a general type of vane pump pump well-known per se. There are many variations of this general type of positive displacement rotary pump, and I do not wish to be limited to this specific rotary pump structure.

The vane pump 20 is driven by means of the gear 25 keyed to the motor shaft 26, this gear 25 being in turn driven by the pinion 24 from the main pump shaft 22, as already described.

One characteristic of this type of positive rotary pump 20 is that its operational range is limited by two general factors. When operating at low speed, the maximum pressure obtainable with this pump is low, because of the slippage past the blade clearances in the pump. As the pump rotational speed is increased, it is capable of higher pressure, because the increased speed allows less time interval for slippage past each vane or blade 93. The pump 20 by its inherent nature has a fixed displacement per revolution, and as the

speed is increased to afford higher differential pressure across the pump, its pumping capacity tries to increase at the same proportionate rate. It soon reaches a point where it is trying to pump liquid faster than the liquid in the suction line can get into the displacement spaces through the suction port of the pump. At this stage in the pump operation, the suction caused by this greater displacement lowers the absolute pressure at the inlet to the pump to a point where it approaches or goes below the vapor pressure of the liquid it is handling. The pump, under these conditions, develops noise and loses liquid capacity and its pressure capability.

15 Pumps 20 of this nature have been used in the aircraft industry as fuel pumps for a long time, and their pressure has always been limited to around 35 p. s. i. differential and a speed of about 2500 R. P. M. Beyond this speed and pressure, 20 the objectionable noise and rapid disintegration of the pump occurs. It has therefore never been envisaged to employ these units for higher pressure operations, such as 200 or 300 p. s. i. differential. Because of this limitation in the operation of the general vane type of rotary pump, in their stead there have been used gear pumps or piston type pumps which can operate at a low speed and at low capacity, and which can deliver the low viscosity liquids against the higher pressures required. Even with pumps of this type, however, they operate at higher pressures to better advantage with high viscosity liquids.

In accordance with my invention, I place the inlet of the conventional vane type rotary pump 35 under pressure so as to enable it to operate at high speeds, and thus obtain high differential pressures, such as 300 p. s. i. and 3500 R. P. M. The pressurizing of the liquid on the inlet side of the rotary pump 20 prevents the cavitation normally 40 experienced at these high speeds, and completely charges the inlet of the vane pump with liquid fuel below the vapor pressure point of the fuel.

The arrangement of the different pumps with their different controls has already been explained in connection with the diagrammatic construction shown in Fig. 5. It has been shown in connection with this arrangement, that under normal operation, the vane pump 20 is not doing any work, and is merely by-passing a quantity of fuel around the circuit 39, 51, 53, 54 and 42, while the centrifugal pump 18 is pumping through conduits 38 to 42.

Even should the control in the main fuel line or atomizer line 48 be shut off, the positive acting pump 20 would not build up pressure while the valve 55 is fully open, because any fuel that could not pass through the fuel pump 43 because of a closed discharge line, would return through conduit 38 back through conduit 39 to the suction 60 of the rotary vane pump 20. The pressure throughout all of these conduits would be essentially at the discharge pressure of the centrifugal pump 18. The discharge pressure of the centrifugal pump 18 would not rise higher than its normal no-flow value, which in this case is approximately 30 p. s. i., because of the centrifugal characteristics of this type of pump by which the maximum pressure is limited by the speed of rotation of the centrifugal pump impeller 33.

If, for any reason, there is a failure of the main high pressure fuel pump 43, or any of the controls coordinated with it, it would nevertheless, under these emergency conditions, be desirable to continue to furnish high pressure fuel to the nozzles in the main line 45. In accordance

with my construction, this emergency operation is accomplished by the throttling of the by-pass valve 55. If this by-pass valve 55 is completely closed, all of the flow through the positive vane type pump 20 is then forced to go through the check valve 56 and into the burner supply line 45. Any back flow into the centrifugal pump 18 or into the disabled main high pressure fuel pump 43 is prevented by the check valve 44.

By means of this arrangement, the vane type rotary pump 20 serves as an emergency main fuel pump operating like pump 43 to deliver fuel at high pressure to the burner supply line 45 as just described when the valve 55 is closed or partly closed. The control of the amount of delivery to the burner nozzles through the line 45 from the vane pump 20 can be effected by adjustment of valve 55. While this valve 55 is open, it by-passes some of the fuel delivered under high pressure by the vane pump 20 back to the suction side of this pump through connections 42, 41, 38 and 39. By the proper adjustment of valve 55, which may be done manually or by automatic means, such as the known barometric compensated relief valve, the required amounts of fuel may be fed by the pump 20 at the required pressure to the burner nozzles through the line 45.

As a protection against the overloading of the motor 17 in cases where higher pressures should be encountered by the pumps than that for which they were primarily designed, a relief valve assembly 100 is provided. This valve assembly comprises a poppet type valve 101 held on its seat 102 by an adjustable spring 103 so arranged that when the desired maximum relief point is reached in the discharge conduit 51, the valve 101 will open and will cause the liquid to discharge back into the tank 10 in which the complete pump unit is located.

As many changes can be made in the above apparatus, and many apparently widely different embodiments of this invention can be made without departing from the scope of the claims, it is intended that all matter contained in the above description or shown in the accompanying drawings shall be interpreted as illustrative and not in a limiting sense.

I have described what I believe to be the best embodiments of my invention. I do not wish, however, to be confined to the embodiments shown, but what I desire to cover by Letters Patent is set forth in the appended claims.

I claim:

1. In combination, a fuel feed line for an internal combustion unit, a pair of branch conduits connected into said line, a main fuel pump in one of said branch conduits, a check valve in said latter branch conduit on the discharge side of said main fuel pump permitting flow to said feed line from said latter branch conduit, but blocking flow in the opposite direction, a fuel booster pump having a branch discharge connection leading to the inlet of said main fuel pump, an emergency fuel pump having its discharge connecting into the other branch conduit, a check valve in said other branch conduit permitting flow to said feed line from said other branch conduit, but blocking flow in the opposite direction, said fuel booster pump having another branch discharge connection connected into the inlet of said emergency fuel pump, a by-pass line between said branch conduits, and a valve in said by-pass line.

2. The combination as described in claim 1, in which said emergency fuel pump is of the rotary

vane type, and said fuel booster pump is of the centrifugal type.

3. In combination, a fuel feed line, a pair of branch conduits connected into said fuel feed line, a main fuel pump in one of said branch conduits, an emergency fuel pump having a discharge leading to the other of said branch conduits, said emergency fuel pump during normal operations of the main fuel pump being insufficient to deliver fuel to said feed line at the required pressure, a fuel booster pump having two branch discharge connections, one of said branch connections leading to the inlet of said main fuel pump and the other to the inlet of said emergency fuel pump, and means for supplying to said line by the operation of said emergency pump, fuel at the required pressure to make up deficiency in said required pressure.

4. The combination as described in claim 3, in which said emergency fuel pump is of the positive rotary displacement type.

5. The combination as described in claim 3, in which said emergency fuel pump is of the rotary vane type.

6. The combination as described in claim 3, in which said fuel booster pump is of the centrifugal type.

7. The combination as described in claim 3, in which said emergency fuel pump is of the rotary vane type, and said fuel booster pump is of the centrifugal type.

8. The combination as described in claim 3, in which said fuel booster pump has means for separating the gases from the fuel being pumped and collecting them near the inlet of said booster pump, and in which there is provided a gas removal pump for pumping the collected gases from said fuel booster pump.

9. The combination as described in claim 3, in which said fuel booster pump is of the centrifugal type with an axial inlet and a peripheral volute discharge, and has an annular gas collecting chamber in its casing surrounding said inlet, and in which there is provided a gas removal pump for pumping the collected gases from said chamber.

10. The combination as described in claim 3, in which said fuel booster pump is of the centrifugal type with an axial inlet and a peripheral volute discharge, and has an annular gas collecting chamber in its casing surrounding said inlet, and in which there is provided a gas removal pump for pumping the collected gases from said chamber, said emergency pump being of the rotary vane type.

11. In combination, a fuel feed line, a pair of branch conduits connected into said fuel feed line, a main fuel pump in one of said branch conduits, an emergency fuel pump having a discharge leading to the other of said branch conduits, a fuel booster pump having two branch discharge connections, one of said branch connections leading to the inlet of said main fuel pump and the other to the inlet of said emergency fuel pump, and means for controlling the amount of fuel admitted from the discharge of said emergency pump to said other branch conduit, whereby deficiencies in required pressure in said line may be made up by the operation of said emergency pump.

12. The combination as described in claim 11, in which said controlling means comprises a by-pass line between the two branch conduits, and a valve in said by-pass line.

13. The combination as described in claim 11, in which said controlling means is operable while maintaining the speed of said emergency pump substantially constant.

14. The combination as described in claim 11, comprising a motor, and means for driving said emergency fuel pump and said fuel booster pump from said motor at a predetermined substantially constant speed ratio.

HAROLD E. ADAMS.
